(57) **CLAIM**

The ornamental design for pizza peel, as shown and described.

DESCRIPTION

FIG. 1 is a plan view of the pizza peel with a pizza over the pizza peel, showing my new design.

FIG. 2 is a side view of the pizza peel along a longitudinal side showing the pizza over the pizza peel.

FIG. 3 is a side view of the pizza peel along a transverse side showing the pizza over the pizza peel; and,

FIG. 4 is another side view of the pizza peel along the transverse side showing the pizza over the pizza peel.

The broken lines are for illustrative purposes only and form no part of the claimed design.
